UNITED STATES PATENT OFFICE.

GEORGE C. SNYDER, OF NEW YORK, N. Y.

METHOD OF ATTACHING FASTENING DEVICES.

1,138,021.

Specification of Letters Patent.

Patented May 4, 1915.

Application filed June 29, 1914. Serial No. 847,938.

To all whom it may concern:

Be it known that I, GEORGE C. SNYDER, a citizen of the United States, residing in the city of New York, county of New York, and State of New York, have invented certain new and useful Improvements in Methods of Attaching Fastening Devices; and I do hereby declare the following to be a full, clear, and exact description of the invention, such as will enable others skilled in the art to which it appertains to make and use the same.

This invention relates to the method of attaching to fabrics and the like, fastening devices of the same general type as those disclosed in my co-pending applications, Ser. No. 837,393, filed May 9, 1914, and Ser. No. 844,434, filed June 11, 1914.

The fastening devices disclosed in these applications consist of the fastening member proper, such as a button or the like, and a tubular thimble which is adapted to be forced into a tubular shank of the button and locked therein, due to a collapsing of the thimble which takes place when the same is forced against the head of the button. A portion of the fabric is carried into the shank of the button by the thimble, and when the same is locked in position, the button is thereby securely attached to the fabric.

The present invention is directed to the general method involved in applying fastening devices of the foregoing character, and is exemplified in the accompanying drawing, in which:

Figure 1 is a sectional view, partly in elevation, of the improved fastener disclosed in my pending application, Ser. No. 844,434, above referred to, showing the parts in position ready to be assembled; Fig. 2 is a corresponding sectional view showing the position of the various parts just before the thimble collapses; and Fig. 3 is a similar view showing the thimble in its collapsed condition and showing the button firmly attached to the fabric.

Referring to the drawing, in which one form of my improved fastening device is shown to illustrate the method, the fastening member proper, which, in the present instance, is a button, is denoted generally by the reference character 1, the head portion of which may be of any suitable construction. A tubular shank portion 2 is provided, which, at its lower edge, has a basal

inturned flange 3, for the purpose to be hereinafter described.

A tubular member or thimble 4 is provided, preferably, but not necessarily, closed at one end and preferably slightly rounded at one end, as best shown in Fig. 2, the thimble being adapted to be positioned in telescopic relation with the shank 2 of the button. In the present instance, the parts are telescoped by forcing the thimble into the shank of the button, the shank constituting the other tubular member referred to in the claims. In Fig. 1, the thimble 4 is shown in position ready to be positioned within the shank 2, and the fabric *a*, to which the fastener is to be secured, is interposed between the thimble 4 and the button. The plunger A, of any suitable assembling mechanism, then descends, and, by means of a suitably formed shoulder A' thereon, which engages the edge portion of the thimble, the latter is forced together with a portion of the fabric *a* into the shank 2 of the button, as shown in Fig. 2. The thimble 4 is of such length that during its descent, the end thereof strikes the head of the button, so that further force applied to the thimble by means of the plunger A will tend to upset or collapse that portion of the thimble which lies within the shank 2. As the plunger A further descends from the position shown in Fig. 2, that end of the thimble within the shank expands and spreads radially in all directions, forming an enlarged bulbous head on the thimble, as shown in Fig. 3. The expanded thimble, therefore, fills up practically the entire space within the shank, 2, and as the expansion of the thimble takes place behind the flange 3, the thimble is securely and firmly locked within the shank of the button. As a portion of the fabric passes behind the thimble, it is obvious that the locking of the thimble in place also securely attaches the button to the fabric.

The diameter of the thimble is such that as the thimble, together with the fabric, passes through the opening in the shank 2, the flange 3 will be deflected to substantially the position shown in Figs. 2 and 3. A tight gripping action on the fabric, therefore, results between the inner edge of the flange and the adjacent portion of the thimble, as exemplified at 3', in Fig. 3.

In my co-pending application, Ser. No. 844,434, it is clearly explained how the inturned flange 3 adapts the button to several

thicknesses of fabric as well as to one thickness. The flange 3 will be deflected a greater or less extent, depending upon the number of thicknesses of fabric to which the 5 button is applied. The said flange 3, therefore, automatically adapts itself to the number of thicknesses of fabric, and the button may be used on all parts of a garment, regardless of the number of thicknesses of 10 material at the point at which the button is applied. The button may be as firmly secured to the fabric in one instance as in the other, and the collapsing action of the thimble is the same when one thickness of material 15 is involved as when a number of thicknesses thereof are involved.

It will be noted that the plunger A, in descending, exerts an axial pressure on the walls of the tubular thimble, and when the 20 thimble contacts with the head of the button, a continuance of the application of this pressure results in the collapsing of the thimble, hereinbefore described, and that portion of the thimble within the shank of 25 the button bulges outwardly, as shown in Fig. 3. The shoulder A' on the plunger A is preferably so shaped as to prevent the peripheral edge of the thimble from slipping off the plunger A, when the thimble 30 comes into contact with the head of the button. This shoulder therefore, confines the peripheral edge of the thimble and prevents that portion of the thimble from expanding while the same is being forced against the 35 head of the button. The entire collapsing action or expansion of the thimble, therefore, takes place behind the flange 3, as clearly shown in Fig. 3.

From the foregoing, it will be seen that 40 in one stroke of any suitable assembling mechanism, the thimble is positioned and collapsed, in the manner hereinbefore described. The same plunger, which positions the thimble, is, therefore, employed to 45 produce the collapsing action. This is permitted by the fact that the pressure exerted by the plunger is applied to the walls of the thimble in a direction parallel therewith. In other words, an axial pressure is exerted 50 at the peripheral edge of the thimble, which results in the formation of the bulbous head on the thimble. It is to be understood, how-

ever, that the term "bulbous", as used throughout the specification and claims, is to be construed as meaning any kind of an 55 enlarged head having lateral walls convexed outwardly, whether the expanded end of the thimble be closed or not.

What I claim is:—

1. The method of attaching to fabric, fastening devices, comprising two tubular members one of which is adapted to be positioned in the other by telescopic action, which method consists in telescoping said members by forcing one of the same and a 60 portion of the fabric into the other and collapsing a portion of the inner member during the telescoping action to form a bulbous head thereon to lock the collapsed member within the other, thereby attaching the fastening device to the fabric.

2. The method of attaching to fabric, fastening devices, comprising two tubular members one of which is adapted to be positioned in the other by telescopic action, 75 which method consists in telescoping said members by forcing one of the same and a portion of the fabric into the other and collapsing a portion of the inner member during the telescoping action to form a head 80 portion thereon having outwardly convexed lateral walls to lock the collapsed member within the other, thereby attaching the fastening device to the fabric.

3. The method of attaching to fabric, fastening devices, comprising an outer tubular member and a tubular thimble adapted to be positioned therein, which consists in telescoping said tubular thimble with respect to the outer member by forcing the tubular 90 thimble and a portion of the fabric into said outer member, and collapsing a portion of the thimble during the telescoping action to form a bulbous head thereon to lock the collapsed thimble within the outer member, 95 thereby attaching the fastening device to the fabric.

In testimony whereof I affix my signature, in presence of two witnesses.

GEORGE C. SNYDER.
